UNITED STATES PATENT OFFICE.

HENRY F. MANN, OF PITTSBURG, PENNSYLVANIA.

BREECH-LOADING ORDNANCE.

SPECIFICATION forming part of Letters Patent No. 257,230, dated May 2, 1882.

Application filed March 2, 1882. (No model.)

To all whom it may concern:

Be it known that I, HENRY F. MANN, a citizen of the United States, residing at Pittsburgh, in the county of Allegheny and State of Pennsylvania, have invented certain new and useful Improvements in Breech-Loading Ordnance, of which the following is a full, clear, and exact description, reference being had to the accompanying drawings, in which—

10. Figure 1 is a perspective view of a gun suitable for fortifications, shipboard, &c., embodying my invention, the breech being closed, as in position for firing. Fig. 2 is a similar view, the breech being open, as in position for loading. Fig. 3 is a side elevation of the gun in position for loading, showing the operative parts. Fig. 4 is a similar view, the breech being closed. Fig. 5 is a longitudinal horizontal section. Fig. 6 is a rear view of Figs. 1 to 5. 15. Figs. 7, 8, and 9 are views showing a modification of the devices for tilting the barrel for the purpose of loading, and Fig. 10 is an enlarged sectional view of Fig. 8.

Like letters refer to like parts wherever they occur.

20. The object of the first part of my invention is to so construct and mount breech-loading ordnance that the strain upon the barrel shall be reduced and its endurance proportionately increased; and this I accomplish by disconnecting the barrel and breech-block and so mounting the parts upon side straps pivoted on a carriage that the barrel is subjected only to lateral or transverse strain due to the expansive force of the charge and the heat developed, while the longitudinal strain is transmitted by the breech-block, cross-head, and breech-screw to the side straps, said parts being aided by the weight or inertia of the barrel.

25. The object of the second part of my invention is to facilitate the opening and closing of the breech, so as to enable the gun to be fired rapidly; and this I accomplish by pivoting the barrel upon the side straps and providing the side straps or breech-block, which is mounted on the side straps, with mechanism for tilting the pivoted barrel.

In addition to these main features there are certain details of construction and specific combinations which tend to simplify the mechanism and render the same more accurate in

operation, all of which will hereinafter more fully appear.

I will now proceed to describe my invention more specifically, so that others skilled in the art to which it appertains may apply the same.

A indicates the barrel of the gun, the bore of which extends from end to end and may be rifled or provided with lands in the usual or any approved manner. The barrel is independent of all connection with the breech-block, and it will therefore be unsupported thereby, or, as in case of a solid breech, it may, where the nature of the metal demands, be re-enforced against lateral strain by reducing or turning down the rear end of the barrel and shrinking bands of wrought iron or steel thereon, as shown at a, and this is perfectly practicable in a gun of the class specified, wherein the barrel is not subjected to longitudinal strain. By preference the reduction of the barrel is such that the bands a shrunk thereon will not materially increase the original diameter. The barrel A is provided with suitable trunnions, a', and is pivoted thereby on side straps, B, either in equilibrium or preponderance, as may be preferred.

30. B indicates the side straps on which the barrel is pivoted. These side straps are connected at the rear by a cross-head or transom, C, through which passes the breech-screw D. The inner face of said cross-head is provided with an annular shoulder, e, which enters a cup on the rear of the breech-block, and the breech-screw D is provided with hand-levers, d or 35. equivalent means for operating the same.

35. Between the rear end of the barrel A and the forward part of the transom or cross-head C is arranged the breech-block E, which block has sufficient longitudinal play, when not forced against the barrel by the breech-screw, to permit the free disengagement of the barrel A and obviate any bad effects from the expansion of the metal or the fouling of the piece. I may here say that it is proposed to use gas checks 40. of any of the several well-known classes, and in such case no trouble from fouling will arise. The rear face of the breech-block E is provided with an annular cup, e, for the reception of the annular shoulder e on the forward part of the cross-head C, whereby the breech-block is centered, and it may be supported and guided,

where required, by guide-pins e' , as shown in Fig. 10. The upper surface of the breech-block E is cut away, as at e^2 , equal to the diameter of the bore, to serve as a rest for the cartridge 5 and facilitate the introduction thereof, as well as well as to reduce the required movement of the pivoted barrel. e^3 (see Fig. 8) indicates the vent-hole.

As before specified, the barrel A is pivoted 10 by its trunnions on the side straps, B, and these side straps serve also to support the breech-block, which is entirely disconnected or detached from the barrel, a cross-head, and the breech-screw. Now, the side straps are in turn 15 provided with trunnions b , by which they are pivoted on a suitable carriage, F, either in equilibrium or preponderance as to the whole weight, as preferred, so that the gun can be elevated or depressed at will by the screw f , 20 which supports the cross-head C.

The preferred form of mechanism for tilting the pivoted barrel A for exposing or closing the breech is shown in Figs. 1 to 6, inclusive, and may be described as follows: On the rear 25 end of the barrel A, next the breech-block, are one or more racks, r , which may be either attached to or formed on the rear end of the barrel, and within the breech-block E is a corresponding set of pinions, p , mounted on a shaft, 30 s , which projects beyond and is journaled in the side straps, B, and provided with a crank, s' , by which the pinions may be operated. The face of the breech-block E is recessed for the reception of the racks r , so that when the breech-block is forced against the end of the barrel by the breech-screw D a tight joint will 35 be formed. By this rack-and-pinion mechanism the barrel may be tilted at will; but in order to arrest the downward movement of 40 the barrel and align it with the breech-block a saddle, T, is provided, which is attached to the side straps, B, just below and near the rear end of the barrel, and to limit the upward movement of the barrel a link, l , is employed, 45 which is pivoted to the rear end of the barrel, as at m , and provided with an arc-shaped slot, which incloses a pin, n , on the fixed saddle T.

A modification of the devices for tilting the pivoted barrel is shown in Figs. 7 to 10, inclusive, in which instance the saddle itself is made in the form of a crank-shaft, T' , is journaled on the side straps, B, is provided with a crank-arm, t , and plays through a slotted block, l' , attached to the under side of the barrel at the 55 rear thereof, so that when the saddle or crank-shaft is rotated it slides in the slotted block l' , and when its greatest eccentricity is uppermost the rear end of the barrel has been tilted, so as to expose the bore ready for loading. 60 When the crank-shaft is at its greatest eccentricity, either above or below, it rests at the front end of the slot in block l' , and thus locks the barrel in the given position.

The construction being substantially as specified, the barrel A will be tilted on its trunnions a' to expose the breech, and the car-

tridge having been inserted, it will be brought down on the saddle to align it with the breech-block E. The breech-screw D will then be turned to take up the slack and force the breech-block home against the end of the barrel. The gun may then be fired in the usual way, when the force due to the expansion will exert the usual lateral strain upon the barrel, which may be re-enforced to resist the same by bands a , if desired; but as the breech-block is not integral with but, on the contrary, is entirely independent of the barrel, the barrel will not be called upon to bear any of the longitudinal strain, except that due to the friction of the shot. 70 The breech-block will transmit the longitudinal strain through the breech-screw and cross-head to the side straps and carriage, and the recoil of the gun will also be resisted by the dead weight of the barrel A, to overcome the 75 inertia of which considerable force will be required.

Among the advantages of my invention are, first, that the barrel is a cylinder, open at both ends, capable of resisting only transverse 80 stresses; and I can therefore calculate the power of the gun to meet that strain and design the gun with certainty. The longitudinal 85 stresses are taken by the side straps, which may be designed with the same degree of certainty of correct proportions. The barrel is balanced upon its trunnions in such manner that it can be readily handled for loading without altering the elevation, and the whole mass is carried by the trunnions of the straps, so that 90 the gun can be promptly elevated or depressed without the exertion of any great amount of force.

The gun consists of a few easily-proportioned and simply-made parts, and stresses due to 95 transfer of heat from part to part are met and obviated.

I do not in this application claim broadly the mounting of the gun on the side straps on different trunnions, as I intend to make this 100 feature the subject of a separate application.

Having thus described my invention, what I claim, and desire to secure by Letters Patent, is—

1. The combination, with a barrel pivoted 115 on side straps, of a breech-block, a transom or cross-head, a breech-screw in the transom or cross-head to operate the breech-block, and side straps pivoted on a carriage, substantially as and for the purpose specified.

2. In breech-loading ordnance, the combination, with a barrel pivoted on side straps, the side straps pivoted on the carriage and having a slotted block on its under side near the breech, of a breech-block and a crank-shaft 125 pivoted on the side straps and passing through the slotted block, the side straps having separate trunnions, substantially as and for the purpose specified.

3. In breech-loading ordnance, the combination, with a barrel reduced and re-enforced at 130 its breech, of side straps in which the barrel

is pivoted on trunnions integral with said barrel, the side straps being pivoted on a suitable carriage by separate trunnions, substantially as and for the purpose specified.

- 5 4. In breech-loading ordnance of the character described, in which the breech-block is connected to the trunnions of the gun by side straps, a rack formed on the rear face of the barrel, a shaft passing transversely through side straps, a pinion or pinions on said shaft to engage the rack, and a crank for turning the shaft, all constructed and arranged substantially as described, for the purpose of opening and closing the barrel.
- 15 5. In breech-loading ordnance, the combination, with a barrel pivoted on side straps, of a saddle attached to the side straps and a slotted link pivoted on the barrel and connected with the saddle, substantially as and for the purpose specified.

- 20 6. In breech-loading ordnance, the combination of side straps having a saddle for the sup-

port of the rear end of the barrel, a barrel pivoted on the side straps and having a rack attached to or formed on its rear end, a slotted link pivoted on the barrel and connected with the saddle, and a breech-block having pinions mounted on a shaft and let into the breech-block, substantially as and for the purpose specified.

25 7. The combination, with a pivoted barrel having a rack on its rear end, of a breech-block having pinions let into it and mounted on a shaft journaled in the side straps, said shaft having lateral play in the breech-block, a cross-head, and a breech-screw, substantially as and for the purpose specified.

30 In testimony whereof I affix my signature in presence of two witnesses.
